UNITED STATES PATENT OFFICE.

JOSEPH Z. WINDER, OF RICHMOND, INDIANA, ASSIGNOR TO RICHMOND FIREPROOF DOOR COMPANY, OF RICHMOND, INDIANA, A CORPORATION OF INDIANA.

FIRE DOOR.

Application filed April 24, 1925. Serial No. 25,633.

My invention relates to a fire door, and more particularly to a swinging door particularly adapted for use in closing the door openings in ware houses.

Doors of the general type to which my invention relates include a metal frame usually made of angle metal stock, the inturned flanges of this frame having firmly secured and fitted thereto a sheet metal plate forming the panel of the door. The metals of different portions of the door vary in thickness, the frames being of heavier stock than the panels, so that when said doors are subjected to high temperatures as in the case of a fire, the door will buckle badly and become so deformed as to make a subsequent opening of the door difficult, and its subsequent use impossible. This condition results mainly from the fact that the panel of the door will expand more rapidly and to a greater extent, by reason of its relatively greater surface dimensions, than the heavier metal angle frame of the door. This is also due in part to the fact that the bulk of material in the panel is relatively less than in the door frame.

With the above conditions in mind, I have provided a fire door which is so constructed as to permit the free expansion of the metal of the panel in all directions without subjecting the frame of the door to any stresses therefrom, while at the same time so reinforcing the door structure as to permit the use of fairly light metal stock in the frame and also in the panel without likelihood of the racking or sagging of the door structure through use. The hinge construction is such that the entire weight of the door will be supported so as to distribute the load throughout the door structure in a manner which will effectively relieve the portion of the door frame adjacent the hinges from excessive strains thereon either from the weight of the door or from its opening and closing movement, the hinge construction being incorporated in the reinforcing members.

In the construction of door as herein described, the panel is supported in relation to the door frame solely by means of friction, thus under normal conditions preventing looseness or rattling of the panel in the frame, yet permitting a free expansion of the panel in the event of the door being subjected to high temperatures as during a fire, with-

out subjecting the frame of the door to stresses as a result of such expansion.

The invention consists primarily in a fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause the frictional engagement of said panel plate between said inwardly directed flanges and said plates, said means not engaging said panel plate, whereby rattling of said panel plate is prevented, and it is permitted to expand in all directions when subjected to high temperatures, and hinge members carried by said frame; and in such other novel features of construction and combination of parts as are hereinafter set forth and described, and more particularly pointed out in the claims hereto appended.

Referring to the drawings,

Fig. 1 is an elevation of a door embodying my invention, said door being broken and condensed both laterally and vertically;

Fig. 2 is a section on the line 2—2 of Fig. 1 through portions of said door only and upon an enlarged scale;

Fig. 3 is a vertical section through the door on the line 3—3 of Fig. 2;

Fig. 4 is an enlarged detail view showing one of the side rails of the door in horizontal section;

Fig. 5 is a similar view showing a modified construction of the door; and

Fig. 6 is another similar view showing a still further modified construction of the frame and panel of the door.

Like letters refer to like parts throughout the several views.

In the embodiment of my invention shown in the drawings *a*, indicates a wall of a building having a door opening therein at *b*. This door opening is closed by a fire door embodying my invention, which door as stated is of the swinging type, fitted within the door opening in a manner which may cause likelihood of the jamming of the door,

in the event of its distortion from expansion in the event of fire adjacent the door.

The construction shown, includes a metal frame *c*, formed of an angle metal bar or 5 bars, one flange *c'* of each bar of the door extending substantially parallel with the wall *a* and flooring within the door opening *b*, and the other angle thereof *c''* being directed inwardly of the frame to form a rabbet 10 opening for the reception of a metal plate *d* forming the panel of the door.

In forming the frame of the door, the flanges *c''* are mitred to permit the formation 15 of the corners, it being possible to form this frame of one continuous angle bar with the ends welded together, or of separate bars thus welded.

The door frame thus described is of a height and width slightly less than the door 20 opening *b*, thus forming a gap about the door when in the closed position which will compensate for variations in the dimensions of different door openings, (supposed to be of the same dimensions) while at 25 the same time affording clearance to permit expansion of the top, bottom and side bars (with certain reinforcing rails to be hereinafter described) without likelihood of causing the jamming of the door in the opening. This gap about the door is closed 30 against the passage of smoke and fire by means of astragals *e* formed by angle metal bars, the flanges *e'* of which close said gaps and lap the door opening, and the other 35 flanges *e''* of which abut against, and are permanently secured to, the flange *c''* of the door frame proper. Said angle bars *e* may be secured to the flange *c''* by being welded thereto, or by being riveted or bolted there- 40 to, as desired.

The bottom bar of the door frame proper is spaced above the threshold, or sill, sufficiently to permit the use of an astragal formed as described at the bottom of the 45 door frame, although if desired, the door frame proper may be brought close to the threshold.

The panel plate *d* is of light metal with the two-fold object of lightening the door 50 structure as much as possible, and reducing the cost of production, rigidity in the door being secured by means independent of the panel. This panel has a very loose fit within the rabbet formed by the inwardly directed flange *c''* of the door frame, the dimensions of this panel being such as to completely close the opening in the door frame, but to space the perimeter or edges of the panel away from the flange *c''* sufficiently 55 to permit the maximum expansion of the metal of the panel when subjected to excessively high temperatures without placing the angle bar frame of the door under any stresses as a result of this expansion, 60 and thus avoid distortion of the door frame 65

from this cause. It will readily be appreciated that with a panel made of light plate metal having the surface dimensions which a panel of this kind will have, the panel, in the event of fire, will expand quickly and to 70 a relatively greater extent than the heavier angle metal frame. By affording sufficient clearance about all edges of the panel, and between same and the flange *c''* of the frame bars, however, such expansion may occur 75 without subjecting the frame to any stresses from the panel, and that furthermore, this expansion, when it occurs, will not result in the buckling of the panel itself, however great the expansion may be, providing of 80 course, that the panel about the edges is not restrained in any way either by the frame or by the means securing the panel within the frame.

It is nevertheless essential that the panel 85 *d* be supported with sufficient permanency to avoid looseness thereof, resulting in rattling, and yet, this securing means must be so constructed and arranged as to permit the free expansion of the panel in the manner above described.

To secure the panel firmly in position in relation to the frame, I provide means secured to the frame of the door in a manner to develop surface pressure upon the panel 90 about and adjacent its edges to hold the panel firmly solely by friction, said means and the rabbet forming flange of the door thus firmly gripping and holding the panel under normal conditions, and yet, in the event of fire, offering insufficient resistance to expansion of the metal of the panel to cause buckling of the panel or deformation of the frame. In this manner the panel is supported in the door frame solely by friction, 95 which will place no restraint upon the free expansion of the panel, and yet will hold it with sufficient firmness to prevent rattling and the presence of gaps between the panel and the frame. In fact the edge 100 of the panel is frictionally held within a channel formed about the opening in the door frame.

In the embodiment of the invention 105 shown, means forming the channel above referred to, and for frictionally holding the panel *d*, consists of a plurality of angle plates or bars *f*, any desired number of such plates or bars of any desired length being used, so long as sufficient friction is developed to hold the panel in the manner above described. One flange *f'* of said angle plates 115 frictionally engages the panel *d* while the other flange *f''* is secured to the flange *c''* of the frame of the door by being riveted or bolted thereto, as particularly illustrated in 120 Figs. 3, 4 and 6, or being welded thereto as shown in Fig. 5. These angle plates or bars 125 do not add materially to the weight of the door, nor do they have any material stiffen- 130

ing action, their purpose being solely to frictionally support the panel with its edges spaced away from the flange c^2 of the door frame.

5 In referring to the light structure of the doors, this is merely a relative term, since of necessity doors embodying the invention will have considerable weight particularly as they are designed to close fairly large door 10 openings in warehouses and are of all metal construction. There is in such doors a weight so distributed that unless braces are provided, there is a great tendency of the door to sag at the points thereof more re- 15 mote from the hinge supports, thus tending to rack it not only from this sagging action but as a result of the frequent jars resulting from the opening and closing of the door. To impart the desired rigidity to the door 20 and avoid the sagging and racking above referred to, while at the same time permitting the frictional support of the door panel for the purposes above described, I provide suitable braces which reinforce the 25 frame of the door against sagging and at the same time afford rigid carrying members for the hinge socket connected with the door and co-operating with a hinge plate upon the door jamb. The construction and 30 arrangement of such braces is such that they will neither support nor be supported by the door panel d .

In the form of the invention shown these braces consist of a channel bar g upon one 35 side of the door extending between opposite vertical flanges c' , the number of these channels preferably corresponding with the number of hinges. Upon the other side of the door are hinge straps h of substantially the 40 same length as the bars g , such bars and such straps being firmly riveted or bolted together and to the flanges c' of the side bars of the door frame. The rivets securing said parts together are indicated at i and where they 45 pass through the panel d , openings are formed in said panel as indicated at d' in Figs. 1 and 2, of sufficient size to permit the expansion of the panel d without placing any stresses upon said rivets, upon the door 50 frame or upon the panel through the bars and straps g and h .

The straps h at the opposite ends thereof rest upon the outer face of the flanges c' upon the side bars of the door and are thus 55 spaced away from the panel d at this face of the door. If desired, this space between the panel and the bar may be closed by a spacer bar j , the thickness of which will be such that the panel will also be frictionally 60 supported at each of these braces in addition to the edge thereof.

Each strap h has formed at one end thereof a hinge socket as h' , the bar being extended beyond the adjacent side astragal e 65 sufficiently to accommodate the hinge socket

k secured to the wall adjacent the door opening.

It will be seen that by the use of braces as described, sagging of the door will be prevented, and that if desired additional frictional supports for the panel may be provided. Particular attention is directed to the fact that aside from the possible frictional engagement above referred to, said braces are unconnected with the panel d . 70 75

By reason of the freedom with which the panel may expand in case of fire, the channels g and the straps h are not relied upon to check buckling of the panel.

To hold the door in the closed position, I 80 provide it with a plurality of pivoted latch members m connected by a link m' so as to cause simultaneous movement of all of said latch members.

At least one of the latch members m is 85 provided with a guide strap m^2 , and said latches are simultaneously actuated by a cam n having a handle n' .

It is to be noted that the latch members m are all pivotally mounted upon the panel d 90 but are unconnected in any way with the door frame although guided in their movements adjacent the edge of the door, by straps o . Each latch member m co-operates with a suitable keeper p mounted on the 95 buck or portion of the wall adjacent the door opening.

In the form of the invention shown in Figs. 1 to 3 and 5, the astragals e and the friction plates f are shown as being secured 100 in relation to the frame of the door by means of welding. In Fig. 5 the construction and arrangement of parts is the same as in Figs. 1 to 4, except that the astragals, friction plate and frame are shown as being riveted 105 together. In the modification shown in Fig. 6, the general construction is the same as that in the other forms of the invention shown, excepting that instead of using angle bars in the frame of the door a T-bar is used, 110 thus combining the frame of the door and the astragals in a single integral part.

In Fig. 6, the foot of the T-bar is indicated at c^3 , this foot corresponding with the two flanges c^2 and e^2 of the other forms of 115 the invention. One portion of the head of this flange is indicated at c^4 , which portion corresponds with the flange e' of the other forms of the invention. The other part of this head represented at c^5 corresponds with 120 the flange c' . In fact, this formation of the frame of the door merely amounts to the substitution of a unitary for a two-part structure as compared with the other forms of the invention.

125 From the foregoing description it will be apparent that the entire load of the door will be supported from the hinges through the straps h , channel bars g and the angle bars e of the frame proper of the door, all 130

these parts being so connected as to provide the desired rigidity in the door structure. With the use of astragals as described, whether the same constitute a separate element secured to the frame, or an integral part of the frame, the door may be fitted within the door opening *b* and still allow sufficient space about the portion of the door within the opening to compensate for the maximum expansion of parts when subjected to a high temperature, and avoid jamming of the door as a result of such expansion. It is also apparent that with a frictionally supported panel, a tight door is secured while maintaining a condition by reason of which the panel may expand freely when subjected to high temperatures, while avoiding buckling of the panel itself or distorting stresses upon the door frame.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause frictional engagement of said panel plate between said inwardly directed flanges and said plates, said means not engaging said panel plate, whereby rattling of said panel plate is prevented, and it is permitted to expand in all directions when subjected to high temperatures, and hinge members carried by said frame.

2. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause frictional engagement of said panel plate between said inwardly directed flanges and said plates, said means not engaging said panel plate, whereby rattling of said panel plate is prevented, and it is permitted to expand in all directions when subjected to high tem-

peratures, braces in frictional engagement with said panel plate and engaging the opposite side bars of said frame, hinge straps upon the side of the door opposite said braces, means rigidly securing each of said braces and each of said hinge straps together and to the side bars of said frame, said panel plate having enlarged openings therein through which said securing means pass, whereby said braces and said straps are unconnected with said panel except frictionally, and hinge members carried by said hinge straps respectively.

3. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause frictional engagement of said panel plate between said inwardly directed flanges and said plates, said means not engaging said panel plate, whereby rattling of said panel plate is prevented, and it is permitted to expand in all directions when subjected to high temperatures, braces in frictional engagement with said panel plate and engaging the opposite side bars of said frame, hinge straps upon the side of the door opposite said braces, a filler plate frictionally engaging said panel plate and between same and each of said hinge straps, means rigidly securing each of said braces and each of said hinge straps together and to the side bars of said frame, said panel plate having enlarged openings therein through which said last named means pass, whereby said braces, said filler plate and said straps are unconnected with said panel except frictionally, and hinge members carried by said hinge straps respectively.

4. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause the frictional engagement of said panel plate between said flanges and said plates, said means not engaging said panel plate, whereby rattling of said panel plate is prevented, and it is permitted to expand in all directions when subjected to high temperatures, hinge mem-

bers carried by said frame, a plurality of latches pivotally supported by said panel plate, a link connecting all of said latches, means operative upon one of said latches for simultaneously actuating all of said latches, and keepers upon the wall of the building adjacent the door opening and cooperating with said latches respectively.

5. A fire door embodying therein a frame of angle metal having one flange of each bar thereof directed inwardly of the frame and another flange thereof extending at substantially right angles thereto to form a rabbeted opening within the frame, the dimensions of said frame being less than the opening to be closed by the door whereby a gap is formed between said frame and the building about the door opening, a metal panel plate closing the opening in said frame but of dimensions which will space the edges thereof away from said last named flanges, plates forming with said inwardly directed flanges a channel, means securing said plates to said frame in a relation to cause the frictional engagement of said panel plate between said flanges and said plates, said means not engaging said panel plate, whereby rattling of said panel plate is prevented and it is permitted to expand in all directions when subjected to high temperatures, a flange carried by, and extending outwardly of said frame, sufficiently to span the gap about same and lap the building structure about the door opening, and hinge members carried by said frame.

6. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause the frictional engagement of said panel plate between said inwardly directed flanges and said plates,

said means not engaging said panel plate, whereby rattling of said panel plate is prevented, and it is permitted to expand in all directions when subjected to high temperatures, channelled braces in frictional engagement with said panel plate and engaging the opposite side bars of said frame, hinge straps upon the opposite side of the door, means rigidly securing each of said channelled braces, and each of said hinge straps together, and to the side bars of said frame, said means passing through enlarged openings in said panel plate, and hinge members carried by said hinge straps respectively.

7. A fire door embodying therein a frame of angle metal having one flange of each bar thereof directed inwardly of the frame and another flange thereof extending at substantially right angles thereto to form a rabbeted opening within the frame, a metal panel plate closing said opening, but of dimensions which will space the edges thereof away from said last named flanges, plates forming with said inwardly directed flanges a channel, means securing said plates to said frame in a relation to cause the frictional engagement of said panel plate between said inwardly directed flanges and said plates, said means not engaging said panel plate, whereby rattling of said panel plate is prevented, and it is permitted to expand in all directions when subjected to high temperatures, channelled braces in frictional engagement with said panel plate and engaging the opposite side bars of said frame, hinge straps upon the opposite side of the door, a filler plate frictionally engaging said panel plate and between same and each of said hinge straps, means rigidly securing each of said channelled braces and each of said hinge straps together, and to the side bars of said frame, said means passing through enlarged openings in said panel plate, and hinge members carried by said hinge straps respectively.

In witness whereof I have hereunto affixed my signature, this 20th day of April, 1925.

JOSEPH Z. WINDER.
